UNITED STATES PATENT OFFICE.

THEODORE LINKE AND HENRY EGBERT GOULD, OF NEW YORK, N. Y.;
SAID GOULD ASSIGNOR TO ANNIE LINKE, OF SAME PLACE.

FILTER FOR LIQUIDS.

SPECIFICATION forming part of Letters Patent No. 554,279, dated February 11, 1896.

Application filed March 19, 1895. Serial No. 542,411. (No model.)

To all whom it may concern:

Be it known that we, THEODORE LINKE and HENRY EGBERT GOULD, citizens of the United States, and residents of New York, in the county of New York and State of New York, have invented a certain new and useful Improved Filter for Liquids, of which the following is a specification.

Our invention relates to an improved filter, which is constructed in such a manner that the water may be drawn therefrom in a filtered state or can be drawn directly without being filtered, and in large quantities.

With the faucet-filters heretofore commonly used it is impossible to draw unfiltered water without removing the filter from the faucet; and the object of this invention is to produce a simple faucet-filter from which it is not only convenient to draw large quantities of unfiltered water, but in which the act of drawing such unfiltered water will cause the filter to be automatically and thoroughly cleansed, thus rendering it unnecessary to remove the filter for cleansing it.

To these ends the invention may be said to consist in the construction and combination of parts substantially as hereinafter described and claimed.

In the accompanying drawing the figure 30 represents a vertical sectional view of the improved filter attached to a faucet.

A represents a bulb, preferably of glass and of the shape shown.

B is a cap having the flange b and a central opening b² provided with a screw-thread, and also provided near the edge with another screw-threaded opening, by means of which the filter is attached to the faucet.

C is a goose-neck having a thread at one end, by means of which it is attached to the cap B in line with the pipe D, which latter is a perforated section of pipe having a screw-thread, by means of which it is attached to the cap B. The other end of the pipe D is closed, or has a plug d inserted therein, and is externally screw-threaded to fit the thread of the upper end of the perforated pipe E. This pipe E is provided with an external thread at its lower end, and is provided with 50 a guide cross-bar e having a square guide-hole to receive the pin f of the valve v.

g is a collar having the milled or polygonal

flange g' and an internal thread at its upper end and the shoulder g² at or near its lower end. The extreme lower end is inverted-cone shaped and forms a seat for the valve v. The valve v has the square extension or pin f, which fits into the square hole of the cross-bar, and has also the threaded stem i.

u is a nozzle having the shoulder n', which fits around the shoulder g² of the collar g, and is also provided with the threaded guide cross-bar n² and has a flange-wheel by which it may be turned.

F is a filtering medium preferably of natural 65 stone, but which may consist of any artificial material. It may be of any convenient shape; but we prefer to make it flat at both ends.

In assembling the parts the pipe D is inserted in a hole cut through the filtering-stone 70 F. Then the cap B is fastened by means of the central threaded hole b² being secured on the pipe D. Between the perforated pipe E and the filter a washer is placed, and the filter is set by screwing up the pipe E. Then the 75 glass bulb A is slipped over the whole, and the edges impinging on a washer placed between the cap B and the bulb. Then a washer e³ is placed next to the bottom of the glass bulb on a seat provided for that purpose, and the square pin of the valve is put in place and the collar g and its attached parts are screwed on. The filter is then ready to be placed on the faucet by fitting the screw-threaded hole b' of the cap to the end of the faucet. Finally 85 the goose-neck C is screwed to the pipe D.

When it is desired to use filtered water, the nozzle is screwed up tight, and thus the valve v is closed. Then the water is forced inward through the filter and passes up through and 90 out of the goose-neck in a very clear and brilliant state. When it is desired to draw a quantity of unfiltered water, it is only necessary to turn the nozzle and the water will flow out, while at the same time the agitation 95 and rapid current of the water will cleanse the filtering-stone.

When the bulb is to be cleaned or emptied of accumulated matter, it will only be necessary to open the nozzle to allow it to escape, 100 the outlet being at the bottom of the bulb.

It is to be understood that we are not confined to the use of the nozzle herein described and illustrated, since a common faucet or pet-

cock may replace the nozzle shown and answer the purpose nearly as well. In fact, any kind of a valve might be used; but for many reasons we prefer the kind shown. Furthermore, the pipe D might be cast with the cap B.

Having now described our invention, what we claim is—

In a filter for liquids, the combination of the bulb A, the perforated pipe D inserted 10 through the same and inclosed in the stone filter F, the cap B having the central opening to receive the goose-neck and the side opening by means of which the whole may be at-

tached to a faucet, the perforated pipe E connected to pipe D and passing through the bottom of and outside of the glass bulb and a valve or cock screwed thereto, all arranged substantially as and for the purpose set forth.

Signed at New York, in the county of New York and State of New York, this 15th day of 20 March, A. D. 1895.

THEODORE LINKE.

HENRY EGBERT GOULD.
